UNITED STATES PATENT OFFICE.

PAUL A. WELLER, OF MAITLAND, MISSOURI.

ATTACHMENT FOR LAMP-CHIMNEYS.

1,137,247.

Specification of Letters Patent. Patented Apr. 27, 1915.

Application filed January 14, 1915. Serial No. 2,209.

To all whom it may concern:

Be it known that I, PAUL A. WELLER, a citizen of the United States, residing at Maitland, in the county of Holt and State of Missouri, have invented a new and useful Attachment for Lamp-Chimneys, of which the following is a specification.

This invention relates to an attachment for lamp chimneys, its object being to provide a simple, durable and efficient support which can be applied readily to an ordinary lamp chimney and which operates to hold small utensils, such as pans, cups or the like above the chimney so that the contents thereof may be heated readily.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings: Figure 1 is a side elevation of the attachment in position, the chimney being shown in section and a portion of a receptacle being indicated by dotted lines upon the attachment. Fig. 2 is a plan view of the attachment. Fig. 3 is a section through the attachment on the line 35 A—B Fig. 1.

Referring to the figures by characters of reference C designates a portion of a lamp chimney, the same being adapted to receive the attachment constituting the present invention. This attachment is preferably made of two lengths of spring wire, each length being doubled or folded at its center and the intermediate or folded portion of said length being twisted together as at 1 to form 45 a stem from which arms 2 radiate. These arms merge into hangers 3 the upper ends of which are bent outwardly as at 4 to form chimney engaging shoulders and from these

shoulders project upwardly converging fingers 5, the upper ends of which merge into 50 radially extending supporting stems 6 the terminals of which are preferably bent upwardly and inwardly as shown at 7 so as to provide rests for engagement with a receptacle R to be heated. It will be noted that 55 the fingers 5 are not secured together at their upper ends but are free to be moved apart so as thus to increase the distances between the rests 7, thereby to adapt the support for use in connection with utensils or 60 receptacles of different sizes. Furthermore as the entire attachment is made up preferably of spring wire, it will be seen that when the same is inserted into a chimney C, the hangers 3 will press outwardly against 65 the chimney and the shoulders 4 will thus be held in engagement with the upper end of the chimney so that the attachment will be properly supported. This attachment will not obstruct the draft through the chimney 70 as the products of combustion and hot gases will be free to flow between the fingers 5 and against the bottom of the receptacle R. Furthermore the attachment will not obscure the light. 75

What is claimed is:—

An attachment for lamp chimneys and the like, comprising separate folded resilient wires, the folded portions of the wires being twisted together to form a stem, said wires 80 being bent to provide radial arms at the upper end of the stem, hangers integral with the arms for engaging the inner surface of the upper portion of the chimney, outstanding chimney engaging portions or shoulders integral with the hangers, upwardly converging fingers extending from said shoulders, and radially disposed supporting stems projecting from the respective fingers. 85

In testimony that I claim the foregoing as 90 my own, I have hereto affixed my signature in the presence of two witnesses.

PAUL A. WELLER.
